SLICED BACON FOLDING AND WRAPPING MACHINE

Alfred C. Gannon, Indianapolis, Ind., assignor to
Kingan & Co. Incorporated, Indianapolis, Ind.,
a corporation of New Jersey

Application July 2, 1947, Serial No. 758,567

10 Claims. (Cl. 93—2)

1

The present invention relates to a machine for folding and wrapping sliced bacon, and the primary objects of the invention is to provide mechanism which will automatically continuously receive, from a slicing station, weighed quantities of sliced bacon, each batch of slices being arranged in the familiar overlapping series upon a sheet of suitable wrapping paper or the like, and then proceed, without attention to fold the projecting lateral edge portions of the sheet over the ends of the bacon slices, then fold a projecting end portion of the sheet over the uppermost few bacon slices of the series, then fold that section of the batch remote from the last-mentioned portion of the paper into overlapping relation with the central section of the batch, then fold the remaining section of the batch into overlapping relation with the first-folded section, and then discharge the completed package. Numerous ancillary objectives will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a side elevation of the feed end of 30 a machine, constructed in accordance with my invention;

Fig. 2 is a similar elevation of the central portion of the machine;

Fig. 3 is a similar elevation of the discharge 35 end of the machine;

Fig. 4 is a plan view of substantially that section of the machine illustrated in Fig. 2;

Fig. 5 is a plan view of substantially that portion of the machine illustrated in Fig. 3;

Fig. 6 is a transverse section taken substantially on the line 6—6 of Fig. 4 and looking in the direction of the arrows;

Fig. 7 is a transverse section taken substantially on the line 7—7 of Fig. 4 and looking in the direction of the arrows;

Fig. 8 is a transverse section taken substantially on the line 8—8 of Fig. 4 and looking in the direction of the arrows;

Fig. 9 is a transverse sectional view taken substantially on the line 9—9 of Fig. 3 and looking in the direction of the arrows;

Fig. 10 is a perspective view, upon an enlarged scale, of one of the carriages incorporated in the

2

machine, parts being broken away for clarity of illustration;

Fig. 11 is a side elevation of such a carriage, bearing a batch of bacon slices associated with a wrapper sheet;

Fig. 12 is a more or less diagrammatic sectional view showing the action of the sheet-edge turning device;

Fig. 13 is a similar view, showing the sheet edge folder elements as they begin to operate;

Fig. 14 is a similar view showing the sheet edge folder elements in final position;

Fig. 15 is a diagrammatic side elevation indicating the action of the sheet end folding mechanism; and

Figs. 16 to 20 illustrate successive steps in the final folding of the bacon package.

Referring more particularly to the drawings, it will be seen that Figs. 1, 2 and 3 may be matched, end to end, to constitute a complete side elevation of the machine. Said machine comprises a frame 30 upon which are supported upper and lower pairs of trackways 31 and 32. Adjacent the feed end of the machine, a pair of sprockets 33 is supported upon a shaft 33' suitably carried for rotation upon a transverse axis, and at the discharge end of the machine, a corresponding pair of sprockets 34 is mounted upon a similar shaft 34'. Near the sprockets 34, a platform 35 is mounted upon the trackways 32 to support an electric motor 36 connected, through a suitable flexible coupling 37, to the input shaft of a gear reduction unit 38 whose output spindle drives, through a chain 39, a sprocket 39' fixed to the shaft 34'.

Likewise fixed to said shaft is a beveled gear 40 meshing with a beveled gear 41 carried at one end of a shaft 42 mounted in suitable bearings 43 and 44 in the machine frame. At its opposite end, the shaft 42 carries the input elements 45 of a toggle joint, indicated generally by the reference numeral 46. The output elements 47 of said joint are supported upon a shaft 48 mounted, for rotation and reciprocation, in suitable bearings 49 and 50 provided in the machine frame. Intermediate its ends, the shaft 48 carries a cylindrical reciprocating cam block 51 peripherally formed with a serpentine cam groove 52 in which engages a roller 53 mounted upon a stationary pillow block 54 suitably supported upon the trackways 32. If desired, the pillow block may be adjustably mounted upon said trackways in order to vary the position of the block 51.

A chain conveyer, indicated by the reference numeral 55, passes about the sprockets 33 and 34

and is thereby led past the trackways 31 and 32. Mounted to travel with the conveyor is a series of carriages, indicated generally by the reference numeral 56, each carriage being provided, at its opposite sides, with ears 57 formed with guide slots 58 (see Fig. 10) adapted to engage the trackways 31 and 32 to guide the movement of said carriages 56.

As is most clearly illustrated in Fig. 10, each carriage 56 comprises a central table 59 to the rearward or trailing edge of which is hinged, at 61, a rear leaf 60. The leaf 60 is formed to provide a proximal section which is normally inclined downwardly and rearwardly from the surface of the table 59, and a distal section which is normally inclined upwardly and rearwardly. A tray 62 is hinged, at 63, to the distal edge of the leaf 60, and projects toward the table 59, being normally held in its illustrated position by a pin 64 slidably extending through the leaf 60, and urged upwardly by a spring 65, one end of which is anchored to the lower end of the pin 64, and the other end of which is anchored to an abutment 66 on the leaf 60. A stop collar 64' on pin 64 limits movement thereof under the influence of spring 65. Likewise hinged at 63 is a flap 67 which is normally inclined upwardly and rearwardly from the distal edge of the leaf 60. One or more springs 68 normally hold the flap 67 in its illustrated position, being anchored between a pin 69 on the flap and a pin 70 on the leaf 60.

Fixed to the lower surface of the flap 67 is an arm 71 projecting downwardly and forwardly from said flap, in the manner illustrated particularly in Figs. 10 and 11, and carrying at its lower end a roller 72. A second arm 73 is fixed to said flap and projects forwardly therefrom at a more acute angle, the arm 73 being considerably longer than the arm 72 and carrying, at its remote end, a roller 74.

An arm 75 projects substantially vertically downwardly, being anchored to the leaf 60, and carries at its lower end a roller 76. A second arm 77 fixed to the leaf 60 is longer than the arm 75, and projects more acutely forwardly therefrom, carrying at its remote end a roller 78. A third arm 79, much longer than the arm 77 and, in the positions of the parts illustrated in Fig. 11, projecting forwardly and slightly upwardly from its anchorage upon the leaf 60, carries at its remote end a roller 80. A spring 81, anchored at one end to the leaf 60 and at its opposite end to a pin 82, normally holds the leaf 60 in its position shown in Fig. 11.

The functions of the various arms and rollers just described, and their manner of operation, will be made clear as the description proceeds.

A forward or leading leaf 83 is hinged at 84 to the leading edge of the table 59; and the leaf 83 likewise comprises a proximal section which is normally inclined downwardly and forwardly from the table, and a distal section which is normally inclined upwardly and forwardly from the table. A tray 85 is hinged at 86 to the distal edge of the leaf 83, and projects therefrom generally toward the table 59. Depending from the rearward edge of the tray 85, and transversely spaced along said edge, is a series of fingers 87, preferably curved upon a common arc concentric with the axis of the hinge 86, the lower ends of said fingers being adapted to extend through and be guided in, transverse slots 88 (see Fig. 10) formed in the leaf 83. It will be clear from an inspection of Figs. 11 and 20 that the fingers 87 are disposed closely adjacent the forward edge of the table 59

and that, when the tray 85 is unloaded, its edge adjacent said table is held above the surface of said table by a plunger 95 guided in the leaf 83 and urged upwardly by a spring 97 anchored to the lower end of said pin and to a fixed abutment on the leaf 83. A stop collar 96' on plunger 95 limits movement thereof under the influence of spring 97. When the edge of said tray is thus held in its elevated position, the fingers 87 act as an abutment adjacent the forward edge of the table 59.

As is clearly shown in Figs. 10 and 11, an arm 89 attached to the distal portion of the leaf 83 projects downwardly and forwardly therefrom and carries at its remote end a roller 90. A second arm 91, fixed to the proximal section of said leaf, and somewhat longer than the arm 89, projects downwardly and forwardly at a less acute angle, and carries at its lower end a roller 92. A third arm 93, fixed to the distal portion of the leaf 83, projects forwardly and upwardly therefrom, and carries at its remote end a roller 94. The functions and manner of operation of these arms and rollers will appear as the description proceeds.

25 A spring 95 is anchored to the leaf 83 and to the pin 82 to hold the leaf 83 normally in the position illustrated in Figs. 10 and 11.

Adjacent the opposite sides of the trackways 31 I provide curved flanges 98 and 99 (see Figs. 2, 4, 30 7 and 12). A bacon batch, indicated generally by the reference numeral 100 in Fig. 11, comprises a sheet 101 of paper, glassine, cellophane, or other suitable wrapping material, upon which have been deposited in the overlapping series arrangement, 35 a plurality of bacon strips indicated by the reference numeral 102. The lowermost bacon strip is customarily placed closely adjacent the leading edge of the wrapper sheet, with its ends substantially equally spaced from the transverse edges of 40 such sheet which project beyond the strip, and successive strips of bacon are similarly arranged. The trailing edge portion 104 of the sheet projects a substantial distance beyond the uppermost bacon strip. Such a batch 100 will be placed 45 upon each carriage 56 in the region illustrated in Fig. 1; and the spring 97 is of such strength that the weight of that portion of the batch which is thrown upon the tray 85 will depress said tray substantially into the plane of the table 59, the leading edge 103 of the batch being substantially 50 coincident with the distal edge of the leaf 83. As the carriage bearing such a batch passes the station at which are positioned the flanges 98 and 99, the projecting edges 105 and 106 of the sheet 55 101 are elevated by engagement with said flanges, substantially into the relation illustrated in Fig. 12.

Immediately adjacent and beyond the flanges 98 and 99, I provide a flying folding mechanism, 60 indicated generally by the reference numeral 107, and best illustrated in Figs. 2, 4 and 6.

A web comprising integral right-and-lefthand supporting elements 108 and 109 is supported, 65 upon the rods 110 and 111, for reciprocatory movement in the line of travel of the conveyor 55. The element 108 has an arm 112, and the element 109 has an arm 113 integrally joined therewith, said arms extending into cooperative engagement with the shaft 48, and being fixed to 70 move axially therewith through the medium of a bearing structure indicated by the reference numeral 114 in Figs. 2 and 6 and common to said arms.

75 A lever 115 is pivotally mounted at 116 upon the supporting element 108 and carries, inter-

mediate its ends, a roller 117 positioned for cooperative engagement with the perimetral surface of an ovoid cam 118 fixed to the shaft 48. A similar lever 119 is pivotally mounted at 120 upon the supporting element 109 and carries a roller 121 positioned for cooperative engagement with the perimetral surface of a similar, but oppositely arranged, cam 122, likewise fixed to the shaft 48. A spring 123 extends between the levers 115 and 119, urging the lower ends thereof toward each other, and thereby holding the rollers 117 and 121 resiliently in engagement with their respective cams 118 and 122.

A link 124 is pivotally connected with the lower end of the lever 115 and the lower end of a lever 125 pivotally mounted intermediate its ends at 126 upon the supporting element 109. At its opposite end, the lever 125 is provided with a lost motion slot 127 in which engages one end 128 of a pusher rod 129 mounted for reciprocation in suitable guide means carried by the supporting element 109. Beyond the guide means, there is hingedly connected at 130 to the end of the rod 129 a presser element 130 whose distal edge is rolled upwardly and rearwardly, as at 131, to provide a smooth and substantially frictionless pusher nose.

Similarly, a link 132 is pivotally connected to the lower end of the lever 119 and to the lower end of a lever 133 pivotally mounted, intermediate its ends, at 134, upon the supporting element 109. The upper end of the lever 133 is provided with a lost motion slot 135 in which engages one end 136 of a pusher rod 137 mounted for axial reciprocation in suitable guide means carried by the supporting element 109. A presser element 138 is hingedly connected at 131 with the opposite end of the rod 137, and the remote edge of said element 138 is rolled upwardly and rearwardly as at 139 to provide a pusher nose similar to the nose 131. Springs 142 and 143 resiliently hold the presser elements 130 and 138 normally in their positions illustrated in Fig. 6.

A lever 144 is pivotally mounted intermediate its ends, at 145, upon the supporting element 109. At one end, said lever carries a roller 146 in cooperative engagement with the perimetral surface of a cam 147 fixed to the shaft 48, said cam being provided with a single projecting pip 148. It will be noted that the apex of the pip 148 is peripherally spaced from the high point of cam 118 a little less than 90° in a clockwise direction and from the high point of cam 122 a little more than 90° in a counter-clockwise direction, and that the roller 146 is substantially midway between the rollers 117 and 121 which are substantially diametrically opposed, relative to the shaft 48.

A link 149 connects the opposite end of the lever 144 with one end of a lever 150, pivotally mounted intermediate its ends, at 151, upon the supporting member 109. A block 152 is pivotally supported, at 153, upon the other end of the lever 150, the connection between said block and said lever being such as to permit some movement of said block toward said lever end, and a spring 154 being provided to oppose such movement. A spring 155, extending between the lever 144 and an anchorage on the supporting element 109, normally holds lever 150 and block 152 in the positions illustrated in Fig. 6.

The relationship between the parts illustrated in Fig. 6 and the cam block 51 is such that, as a carriage comes into registry with the folding mechanism 107, the lateral edges of its supported

sheet 101 being held in the elevated positions illustrated in Fig. 12, by the flanges 98 and 99, the shaft 48 begins to move, in the direction and at the velocity of movement of the carriage, and the cams 118 and 122 engage the rollers 117 and 121 to swing the levers 115 and 119 outwardly about their pivotal axes 116 and 120.

Thus, the upper ends of the levers 125 and 133 are swung inwardly to project the rods 129 and 137 similarly inwardly. The noses 131 and 139 of the presser members 130 and 138 are thus caused to swing the sheet portions 105 and 106 inwardly. As the cams turn in a counter-clockwise direction from the positions illustrated in Fig. 6, the pip 148 engages the roller 146 to press the block 152 into engagement with the presser element noses 131 and 139 before the high points of the cams 118 and 122 reach cooperative engagement with the rollers 117 and 121. Thus, the presser element noses hold the wrapper edges 105 and 106 in engagement with the bacon slices 102 during the latter portion of the inward movement of said presser elements to exert a smoothing and stretching effect upon said wrapper edges, thus ensuring a relatively tight fold at each edge of the package, and a smooth engagement of the inturned wrapper edges with the bacon. The apex of the pip 148 leaves the roller 146 to release the block 152 just before the presser elements 130 and 138 reach their innermost positions, whereupon the springs 142 and 143 lift the presser elements out of contact with the wrapper edges. Thus, throughout engagement of the presser elements with the wrapper edges, said presser elements are moving inwardly, and said presser elements leave the wrapper edges before their inward movement is arrested. The wrapper edges, of course, adhere to the greasy bacon.

As will be clear from an inspection of Fig. 6, the folding operation is completed and the block 152 is lifted within the first quarter-revolution of the shaft 48. Reference to Fig. 2 will show that during that quarter-revolution, the shaft 48 and its associated parts will be travelling toward the left; and the parts are so proportioned and designed that the velocity of the folder 107 will be identical with that of the carriage 56 with which it currently registers.

During the succeeding quarter-revolution of shaft 48, the high points of cams 118 and 122 will retreat from the rollers 117 and 121 to permit the spring 123 to return the levers 115 and 119, and so the rods 129 and 137, to their starting positions illustrated in Fig. 6. The cam groove 52 is so designed as to effect continued travel of the folder 107 in synchronism with such carriage substantially throughout this period of withdrawal of the rods 129 and 137 in order to guard against any possibility of interference between the presser members and parts of any carriages. But during the third and fourth quarters of the shaft revolution, while the rollers 117, 121, and 146 engage low concentric regions of their associated cams, that portion of the cam groove 52 not shown in Fig. 2, cooperates with the fixed-position roller 53 to reverse the direction of movement of the shaft 48 and its associated parts, and to return the parts to the starting positions shown in Fig. 2.

As the carriage leaves the folding station, the roller 72 on the arm 71 encounters a stationary cam 156 (see Figs. 2 and 4) suitably supported between the trackways 34; and the rising surface of said cam, which is followed by the roller 72, causes the flap 67 to be swung, in a counter-

clockwise direction, sufficiently to move the roller 74 into position for cooperation with a second stationary cam 157. As the roller 74 follows the rising surface of the cam 157, the counter-clockwise swing of the flap 67 is completed, to bring the parts into the position illustrated in Fig. 15, whereby the projecting trailing rear end portion 104 of the sheet is folded forwardly over the rear-most slices of bacon, where said portion will adhere in the manner above-described. At about the moment when the roller 74 reaches the peak of the cam 157, the roller 76 encounters a stationary cam 58; and as said roller follows the rising surface of the cam 158 the leaf 60 is swung in a counter-clockwise direction about its hinge axis 61. The cam 158 is capable of moving the leaf 60 only to the position illustrated in Fig. 16. Of course, the roller 74 is lifted off its cam 157 by this action of the leaf 60.

As will be apparent from an inspection of Figs. 2 and 3, the roller 90, carried by the arm 89, encounters a stationary cam 159 substantially at the moment when the roller 76 encounters the cam 158. Since the arm 89 is forwardly and downwardly inclined, travel of the roller 90 up the inclined surface of the cam 159 will swing the leaf 83 in a clockwise direction about its hinge axis 84. Coaction between the roller 90 and the cam 159 swings the leaf 83 far enough to bring the roller 92, on the arm 91, into position to encounter, cooperatively, a stationary cam 160; and as the roller 92 rides up the cam surface 160, the leaf 83 is swung in a clockwise direction as illustrated at the righthand end of Fig. 3. Now, the parts occupy substantially the positions illustrated in Fig. 16. It is to be noted that the two leaves 60 and 83 move substantially simultaneously from the positions of Fig. 15 to the positions of Fig. 16, so that each leaf acts as an abutment preventing bodily shifting of the bacon batch 100 under the influence of the folding action of the companion leaf.

Now, while the uppermost plateau of the cam 158 coacts with the roller 76 to hold the leaf 60 in the position illustrated in Fig. 16, the roller 94 on the arm 93 encounters a stationary cam 161, and as said roller follows said cam, the folding action of the leaf 83 is completed, the parts being brought into the positions illustrated in Fig. 17, whereby substantially the leading one-third of the bacon package is folded over into superposition upon the middle one-third of the batch.

Now, as the carriage continues to travel, the roller 94 leaves the cam 161, and the spring 95 returns the leaf 83 toward its starting position, until the roller 92 encounters the descending cam section 164. Substantially simultaneously, the roller 78, on the arm 77, encounters an ascending cam surface 163 so that, as the leaf 83 moves in a counter-clockwise direction, the leaf 60 also moves in a counter-clockwise direction, tending to fold the trailing one-third of the bacon package into superposed relation to the folded, leading one-third. It is to be noted that, as this folding action begins, the leaf 83 and tray 85 act as an abutment to prevent bodily shifting of the package under the influence of such movement of the leaf 60; and, as the tray 85 leaves contact with the package, the fingers 87 continue to act as an abutment. As the roller 78 rides the surface 163, the roller 80 is brought into position to encounter, cooperatively, a rising stationary cam 165; and the coaction between said roller 80 and cam 165 completes the fold-

ing of the trailing portion of the package, bringing the parts into the positions illustrated in Fig. 19. The roller 80 then descends the cam surface 166 to bring the roller 78 into cooperative relation with the descending cam 167, while the roller 92 descends the cam 168, whereby the parts are returned to starting relation at the discharge end of the machine. The fingers 87 still abut the package 100, in the manner illustrated in Fig. 20, and the package may be removed from the machine in any desired way, or may be permitted to drop from the carriage as the carriage passes around the sprocket 34.

The provision of the trays 82 and 85, together with resilient means tending to hold them spaced from the adjacent sections of leaves 60 and 83, is quite important aside from the fact that they establish abutments holding the bacon batch against undesired movement during the batch-folding operations. Bacon batches of the type here under consideration will vary somewhat in thickness in a direction normal to the wrapper 101. While that variation is not numerically large, it will be seen that, at the station illustrated in Fig. 17, the effect of the variation will be doubled, while at the station illustrated in Fig. 19, that effect will be tripled. The spring-pressed trays provide for the exertion of a standard degree of pressure upon the folded batch, whether or not the current batch is of the maximum thickness which the machine is capable of handling, as illustrated in the drawings.

Preferably, relatively heavy frame plates 169 and 170 will be provided for supporting the folding mechanism 107, its shaft 48, and its rods 110 and 111.

I claim as my invention:

1. A package folding machine comprising a guided conveyor, a plurality of carriages serially associated with said conveyor to move therewith, each of said carriages comprising a table, a leaf hingedly associated with the leading edge of said table, a second leaf hingedly associated with the trailing edge of said table, a flap hingedly associated with the trailing edge of said second leaf, follower means associated with said flap; a first cam means associated in the path of said follower means and operable, when engaged by said follower means, to swing said flap upwardly and forwardly into substantial engagement with said second leaf, a second follower means associated with said second leaf, a second cam means disposed in the path of said second follower means and operable, when engaged by said second follower means, to swing said second leaf upwardly and relative to said table, a third follower means associated with said first leaf, a third cam means disposed in the path of said third follower means and engageable thereby substantially concurrently with engagement of said second follower means with said second cam means, said third cam means coacting with said third follower means to swing said first leaf upwardly relative to said table, a fourth follower means associated with said first leaf, a fourth cam means disposed in the path occupied by said fourth follower means after such swinging movement of said first leaf, said fourth cam means coacting with said fourth follower means to swing said first leaf rearwardly and downwardly into overlapping substantially parallel relation with said table, and then to release said follower means, a fifth follower means associated with said second leaf, a fifth cam means disposed in the path of said fifth follower means and coactive therewith, after release of

said fourth follower means, to swing said second leaf forwardly and downwardly into overlapping substantially parallel relation with said table, and means active thereafter to return said leaves to positions located, respectively, wholly in advance of and behind said table.

2. For use in a wrapping and folding machine, a carriage comprising a table, a front leaf hinged to the front edge of said table, a rear leaf hinged to the rear edge of said table, a flap hinged to the rear edge of said rear leaf, and a plurality of cam-followers projecting from each of said hinged elements at various angles.

3. The carriage of claim 2 including spring means for each of said hinged elements resiliently tending to hold each element in a predetermined relation to the element from which it is supported.

4. The carriage of claim 2 in which each leaf is substantially L-shaped in section transverse to its hinge axis.

5. For use in a wrapping and folding machine, a carriage comprising a table providing a substantially horizontal, upwardly-presented surface, a front leaf hinged to said table at the front edge of said surface, a rear leaf hinged to said table at the rear edge of said surface, each of said leaves including a portion adjacent said surface normally inclined downwardly and away from said surface and a distal surface inclined upwardly and away from said surface, a tray for each of said leaves hinged to the distal edge of its leaf and projecting toward said table, and

resilient means supporting the free edge of each of said trays.

6. The carriage of claim 5 in which the free edge of the tray associated with said front leaf is provided with abutment means disposed closely adjacent the front edge of said table, and in which the resilient means for said tray normally supports said tray edge at an elevation above said surface.

7. The carriage of claim 6 in which said abutment means comprises a plurality of transversely-spaced straps depending from said tray edge.

8. The carriage of claim 7 in which said straps are rigid and in which each strap passes through a slot in said front leaf.

9. The carriage of claim 8 in which each strap is curved upon an arc concentric with the hinge axis of said tray.

10. The carriage of claim 5 including a flap hinged to the distal edge of said rear leaf and normally inclined upwardly and away from said surface.
